BY

Wm. H. Lee

ATTORNEY

UNITED STATES PATENT OFFICE

RALPH D. EDWARDS, OF OSCEOLA, INDIANA

SIPHON

Application filed May 20, 1931. Serial No. 538,828.

My invention relates to siphons and particularly to such devices as are particularly adapted for separating the cream from the milk in ordinary milk bottles.

- 5 An object of the invention is to produce such a siphon which may be automatically charged and started into operation without resorting to outside pressure or relatively moving parts.
- 10 Another object is to provide a one piece siphon which may be easily and cheaply manufactured and which will be easily kept in a sanitary condition.

15 A further object is to provide adjustable means for regulating the level to which the siphon will draw off the cream.

20 Other objects of the invention not specifically enumerated will become apparent during the course of the following detailed description when read in conjunction with the accompanying drawing which forms a part of this specification, and in which:

25 Figure 1 is a side elevational view of an embodiment of the invention shown in position in a milk bottle;

Fig. 2 is a view taken at right angles to Fig. 1;

Fig. 3 is a side elevational view with the siphon shown in charging position; and

30 Fig. 4 is a perspective view of a connecting strap employed in the invention.

Referring now to the drawing in detail, wherein like numerals refer to like parts throughout the same, my improved siphon tube 5 comprises a single length of tubing bent upon itself to form two communicating legs 6 and 7. The leg 6 is adapted to extend down inside the neck 8 of a milk bottle 9 and the leg 7 is adapted to extend downwardly outside of the bottle 9 as clearly shown in Figs. 1 and 2, the leg 7 being slightly longer than the leg 6.

The leg 7 is bent away from the leg 6 to provide a diverging portion 10 to clear the 45 bulging side of the bottle 9. The end of the diverging portion of the leg 7 terminates in an outwardly extending open end portion 11 for the delivery of liquid from the siphon.

The leg 6 of the siphon which is prefer- 50 ably parallel with the upper portion of the

leg 7 extends down inside of the bottle 9 and is provided with a substantially hook shaped lower end comprising a laterally extending portion 12 which extends at an angle from the main leg portion 6 and which terminates in 55 a substantially horizontal end portion 13, formed by bending the tube back so as to intersect the center line of the leg 6 of the siphon at substantially right angles. The open end 14 of the horizontal terminal portion 13 preferably extends the same distance past the center line of the leg 6 to one side of the bend 15, connecting the lateral portion 12 and horizontal portion 13 is offset to the 60 other side.

A metal strap 16, having an eye 17 formed at either end, extends between the parallel portions of the legs 6 and 7, said legs being received in the eyes 17 of said strap.

The slide may be frictionally adjusted up 70 and down on the legs so that in addition to strengthening the siphon and protecting the bend 18 between the legs from breakage, the strap also regulates the depth to which the intake portion 13 of the siphon may extend 75 into the bottle. The strap 17 rests on the edge 19 of the mouth of the bottle while the cream is being siphoned off.

In operation, the leg 6 of the siphon is first inserted into the bottle as shown in Figs. 80 1 and 2, the outer end 11 of the leg 7 is then closed with the thumb or finger and the siphon is then raised and tilted to the position shown in Fig. 3, with the intake end 14 still immersed in the cream and with the 85 main portion of the siphon inclined downwardly at an angle from the rim of the bottle. As the trapped cream occupies the leg 6 from the end 14 to a point past the junction of the lateral portion 12, the cream will 90 flow on down to the bend 18 when the finger is released from the end 11 and then back up the leg 7 toward the end 11 until it reaches the level of the cream in the bottle, thus completely charging the siphon with cream. 95 With the siphon thus charged it is returned to the position shown in Figs. 1 and 2 and the cream continues to flow as will be readily understood until the level of the cream falls 100 below the intake end 14.

5 The strap 17 being vertically adjustable on the legs 6 and 7 makes the siphon particularly well adapted for the removal of cream from both pint and quart bottles and permits adjustment for removing just the right amount of cream regardless of the amount on top of the milk in the bottle.

10 Although a preferred embodiment of the invention has been shown and described, it will be understood that various changes in the details of construction may be made without departing from the spirit of the invention as defined by the appended claim.

I claim:

15 A substantially U-shaped siphon formed from a length of tubing bent upon itself to provide a pair of communicating legs, the legs having a main body portion substantially in the same plane with one leg being shorter than the other, the shorter leg being adapted to be disposed within a container, the longer leg being located externally of the container, said shorter leg having a free end portion located at a right angle to the plane passing through the main body portions of the legs and an angular portion connecting the free end portion with the body portion, the free end portion and the angular portion providing means for priming the siphon when the free end portion and angular portion having been submerged in a liquid in the container and the main body portions of the legs have been moved to a downwardly inclined position exteriorly of the container.
